UNITED STATES PATENT OFFICE.

JAMES A. CULTRA, OF OMAHA, NEBRASKA.

ELECTROTHERAPEUTIC APPLIANCE.

Application filed October 20, 1924. Serial No. 744,740.

My invention relates to electrical apparatus for therapeutic uses. It is the object of my invention to provide appliances by which electrical current of any suitable and desired character may be applied to the body, the application of the electric current being confined or limited to a definite area, the area of treatment being apportioned or subdivided into a plurality of subordinate areas through which the current is passed successively or in a definite progression, so that each subordinate area may receive the current for a predetermined period of time and the several areas or conductive paths receive the current in a definite sequence, whereby to effect a progressive and rhythmic or uniformly recurrent cycle of action upon the tissues comprised within the entire area under treatment. Some of the therapeutic effects and advantages attainable by my improved appliances will be set forth hereinafter, as the same may be more readily perceived when considered as functions of the apparatus.

In the accompanying drawings, Fig. 1 is a diagrammatic view of an apparatus embodying my invention, Fig. 2 is an axial section of the distributor employed therein, Fig. 3 is a diagrammatic view, representing the use of applicators in which the multiple contacts have a circuitous or annular arrangement, and Fig. 4 is a similar view, representing the use of applicators having the multiple contacts in a rectilinear arrangement.

The apparatus provided by my invention consists, broadly, of a distributor and pairs of multiple-contact applicators which are connected with the distributor to receive current therefrom. The distributor is supplied from any suitable source with electrical current of any desired therapeutic character, such as high-frequency alternating or diathermic current, low-frequency alternating, sinusoidal or shocking current, direct current either uniform or pulsating, or any combination of the various forms of electrical current which may be employed for therapeutic uses. The applicators are ordinarily provided in pairs, adapted for placement upon substantially opposite sides of the portion of the body which is to be treated, and are characterized by multiple contacts, or plates of conductive material which are separated and insulated from each other, and each of which is supplied with

current from the distributor by an independent conductor. The body portions of the applicators are preferably of flexible, waterproof, insulating material, such as rubber, so as to be readily conformable to the contours of the body, and to be substantially unaffected by the saponaceous or other liquids which may be employed for securing efficient electrical connection between the applicator-contacts and the skin of the patient. The contacts are of suitable conductive material, usually metal of a substantially non-corrodible character, such as pure tin, and are affixed to or embedded in the sheet of insulating material so as to be exposed at one side thereof. Separate wires are connected with the several contact-plates, and for practical convenience the wires from each applicator may be grouped in a cable, the latter extending to a plug or multiple-terminal connector adapted for detachable connection with a corresponding device permanently connected with the distributor.

Referring to the distributor represented in Fig. 2, there is provided a casing consisting of a pair of cup-shaped members 10 and 11 having flanges 12 at the open ends thereof, said flanges being secured together by screws 13 which are also employed to secure the casing to the supports 14. At the closed ends of the casing-members 10 and 11 are plates 15 and 16 of insulating material. Near the central portions of said insulating plates are secured the continuous conductive rings 17 and 18, with which the wires 19 and 20 are connected, said wires being extended from the casing through insulating bushings, and being connected with the desired source of current-supply for the distributor. Upon the outer portions of the plates 15 and 16, concentric with the rings 17 and 18, are secured the segmented rings 21 and 22, and with the several segments of said rings are connected the wires 23 and 24, which are extended from the casing through insulating bushings, then grouped into cables and carried to the plugs or multiple-terminal connectors for connection with corresponding members on the applicator-cables. A shaft 25 is mounted revolvably at the center of the distributor-casing, said shaft extending through a packing-gland 26, and carrying at its outer end a clutch-plate 27 adapted for connection with a driving member 28. The latter is actuated by any mechanical means suitable for rotating the distributor-shaft continu-

ously at the desired speed. Upon the shaft 25 within the casing is secured a spool-shaped collar 29, to the ends of which are secured the bars 30 and 31. Upon said bars 5 are mounted the brushes 32 and 33 which are insulated from the bars and adapted to continuously engage the rings 17 and 18 during rotation of the shaft 25. Also mounted upon and insulated from said bars are the brushes 10 34 and 35 which engage the segmented rings 21 and 22 so as to successively engage the segments thereof during rotation of the shaft. The pairs of brushes on the respective bars are connected to each other by 15 wires 36 and 37, so that through said wires and the brushes the ring 17 is connected successively with the segments of the ring 21, while at the same intervals the ring 18 is connected with the corresponding segments 20 of the ring 22. The distributor-casing may be filled with a suitable insulating fluid, such as oil, to prevent arcing at the brushes when high-tension current is being used.

Referring now to Fig. 1, there is indicated 25 a pair of applicators comprising the insulating sheets 38 and 39 which carry, respectively, the contact-plates 38^a, 38^b . . . 38ⁱ, and 39^a, 39^b . . . 39ⁱ, said contact-plates being arranged in a circuitous or annular series. 30 From the contact-plates of the applicators the wires 40 and 41 extend to the multiple-terminal plugs or connectors 42 and 43, which are detachably connected with the corresponding members 44 and 45 carried at 35 the ends of the distributor-cables containing the wires 23 and 24. The wiring is so arranged that the contact-plates 38^a, 38^b . . . are connected respectively with the segments 21^a, 21^b . . . of the ring 21 of the 40 distributor, and the contact-plates 39^a, 39^b . . . similarly connected, respectively, with the segments 22^a, 22^b . . . of the distributor-ring 22. It will be seen that when 45 the applicators are placed upon opposite sides of the body, electric current supplied to the distributor-terminals 19 and 20, and the distributor-shaft rotated, the current will be caused to pass through the intervening body-tissues between successive pairs of 50 the applicator-contacts, 38^a to 39^a, 38^b to 39^b, and so on throughout the cycle of operation.

Applicators with annularly arranged 55 series of contacts, such as above referred to, may be advantageously employed for treatment of the abdominal region of the trunk, one of the applicators being placed at the back beneath the body, and the other placed upon the abdomen, so that each contact-plate 60 of the upper applicator is substantially vertically opposite the corresponding contact-plate of the lower applicator, as indicated diagrammatically in Fig. 3. For treatments of the abdominal area, it is preferable 65 that the applicators be so arranged that

the progression or sequence in which the current is supplied to the several contacts be clockwise in direction at the anterior applicator, thus corresponding with the direction of peristaltic action in the colon, which 70 is normally so positioned in the subjacent tissues as to substantially parallel the annular series of contacts. The rate at which the distributor is operated may also be controlled so that the rate of progression of the 75 cellular stimulus, caused by the passage of the electric current through the successive paths between corresponding pairs of the applicator-contacts, will substantially coincide with the normal rate of progression of peristaltic waves in the colon. 80

In Fig. 4, I have represented diagrammatically a pair of applicators 46 and 47, having contacts 46^a, 46^b . . . 47^a, 47^b . . . arranged in a rectilinear series. Applicators 85 of this type are suitable for use on anatomical areas, such as the arms, legs and spine, wherein the general direction of the structural organs, such as blood-vessels, nerves, 90 bones, muscles, and lymphatic canals, is longitudinal, or so as to be substantially parallel with the series of applicator-contacts. These applicators are so connected with the distributor that the electric current will be supplied to transversely opposite 95 pairs of the contacts, such as 46^a to 47^a, 46^b to 47^b, and so on. The direction of progression or sequence in which the current is supplied to the successive pairs of contacts, 100 may be chosen according to the effects which are desired to be attained, being either from the proximal to the distal, or from the distal to the proximal extremities of the area of treatment.

By the use of applicators having multiple 105 contacts, supplied with electric current successively or progressively from a suitable distributor, in accordance with my invention, it will be apparent that the cellular 110 stimulus of the tissues in the area of treatment may be applied in a wave-like manner, the tissues in the successive paths traversed by the current first receiving a stimulus during the passage of the current, then reacting physiologically to such stimulus, and finally, if the rate of motion of the distributor is properly timed, having a period 115 of rest or quiescence in which to resume a normal activity. It will also be apparent that by the arrangement of the multiple-contact applicators so that the current passes between successive transversely opposite 120 pairs of the contacts, the distribution of the current throughout the area of treatment will be more uniform than could be attained by the use of single-contact applicators covering the same general area, as the latter would enable the major portion of the transmitted current to pass through low-resistance 125 tissues positioned between any portions 130

of the applicators, to the substantial exclusion of paths of higher resistance.

Now, having described my invention, what I claim and desire to secure by Letters

5 Patent is:

1. In an electro-therapeutic appliance, an applicator comprising a sheet of flexible waterproof insulating material, a series of conductive contact-plates having exposed 10 surfaces at one side of said sheet, and separate conductors connected with the several contact-plates and distributively connected with a source of electrical energy.

2. In an electro-therapeutic appliance, a pair of applicators each comprising a flexible sheet of insulating material and a series of conductive contact-plates having exposed surfaces at one side of said sheet, and separate conductors connected with the several contact-plates and distributively connected with a source of electrical energy, whereby said electrical energy may be transmitted progressively through successive portions of a body interposed between the applicators. 15 20
